UNITED STATES PATENT OFFICE.

GEORGE FRANCIS HOGAN, OF CHICAGO, ILLINOIS.

ENVELOPE MACHINE.

Application filed February 14, 1923. Serial No. 618,912.

To all whom it may concern:

Be it known that I, GEORGE FRANCIS HOGAN, a citizen of the United States, residing at Chicago, in the county of Cook,

5 State of Illinois, have invented certain new and useful Improvements in Envelope Machines; and I do hereby declare the following to be a full, clear, and exact description of the invention, such as will enable others 10 skilled in the art to which it appertains to make and use the same.

This invention relates to machines for manufacturing envelopes and particularly to certain improvements therein.

15 Envelopes are made in automatic machines, and the present invention is applicable particularly to envelope machines of the "tube" type. In machines of this type the paper or other material from which the 20 envelopes are formed is drawn as a web from a roll and passes continuously through the machine to the point where the envelopes are fully formed and severed from each other. The formed envelopes are severed by

25 a revolving knife which cuts the bottom flap of one envelope from the top flap of the other. The bottom flap is then gummed, folded and subjected to pressure which causes it to adhere. The web may be printed before it is placed in the machine or 30 printing mechanism may be associated therewith to apply the desired impression to the web as it passes through the machine.

For certain purposes an envelope with 35 only a bottom flap is required, the top being open and having a thumb notch. Heretofore it has been necessary in producing such envelopes in automatic machines to sever the envelopes and cut the thumb notch by separate operations requiring additional mechanism and reducing the accuracy with which the envelope is formed to the desired size.

It is the object of the present invention to facilitate the manufacture of single flap envelopes by the provision of means whereby the envelopes are severed and provided with a thumb notch in a single operation, the device being adjustable preferably so that the thumb notch may be positioned as 45 required with reference to the lateral edges of the envelope.

Further objects and advantages of the invention will be apparent as it is better understood by reference to the following 50 specification and accompanying drawing, in which

Fig. 1 is a view in perspective illustrating the present invention as applied to an envelope machine;

Fig. 2 is a diagrammatic view illustrating 60 the web before and after the envelopes are severed;

Fig. 3 is a view in perspective of the shearing knife; and

Fig. 4 is a plan view of the finished envelope.

The machine, with the exception of the shearing mechanism, is one which is well known and in common use. Consequently a description thereof is not essential in order 70 that the advantages of the present invention may be clear. In the machine the web is folded and notched as indicated in Fig. 2 and is substantially complete except for the severing operation which is a peculiar function of the present invention.

As above indicated, it is the object of the present invention to sever the envelopes in a single operation, forming simultaneously the flap at the end of one envelope and an 80 edge with a thumb notch at the adjacent end of the next envelope. Before severing the envelopes, the web passes between rolls 5 and 6 which cooperate to draw the web through the machine, the rolls being suitably driven for this purpose. Directly in front of the rolls 5 and 6 a die 7 is supported on the bed of the machine in adjustable relation thereto. The die is provided with a slot 8 which forms a shear with a 90 knife 9 which cooperates therewith. One side of the slot is provided with a semi-circular recess 10 corresponding to the thumb notch 11 which is to be cut in the rear edge of the envelope 12 as indicated 95 in Fig. 4. The knife 9 is rectangular in section and is provided with two sharp lower edges 13 adapted to cooperate with the edges of the die 7. The knife is mounted on a circular support 14 which in turn is 100 carried by a shaft 15 mounted in a bearing 16. The shaft is driven from the source of power, and as the support rotates the knife is brought periodically into cooperating relation with the die. The knife is provided 105 at one side with a projection 17 corresponding in form to the recess 10 in the die. Preferably the knife is mounted in adjustable relation with its support 14 as, for example, by means of a slot 18 and bolts 19. By adjusting the knife 9 and the die 7 the 110 relation of the notch to the lateral edges

of the envelope may be changed readily. The thumb notch is usually disposed in the center of the upper edge of the envelope, but it may be desirable to have it near one of the lateral edges of the envelope.

As the web advances beneath the rollers 5 and 6 the connecting portion 20 which forms the lower flap of the envelope will be positioned above the slot 8 in the die 7. The rotation of the support 14 is so timed with respect to the movement of the web that at the instant noted the knife will descend and shear the web, leaving the flap 21 on one envelope and cutting the adjacent end of the other envelope so that the thumb notch 11 is formed therein. The web is cut simultaneously in two transverse lines spaced apart, no flap being formed on the notched end of the envelope. In this manner the result which has necessitated two operations heretofore is accomplished by a single movement of the knife.

From the foregoing it will be observed that by the provision of means for simultaneously severing the web in two spaced lines I am enabled to produce envelopes of the desired conformation in the simplest and most efficient manner. There is a slight waste of paper in this operation owing to the desirability of avoiding an unsightly projecting tab on the flap of the envelope. The paper lost in the operation is, however, of minor importance in view of the advantages obtained. The invention is particularly desirable in that it ensures uniformity of the product. Each envelope is identical in form with every other envelope produced on the machine, the length of the envelope being fixed when the machine is set and invariable thereafter.

It is to be understood that various details of the arrangement described may be changed and that the invention may be ap-

plied to machines differing in detail from that illustrated in connection with this application, the essential feature being the means for advancing the web and for simultaneously shearing the web in two lines spaced from each other.

I claim:—

1. In an envelope machine, the combination of means for advancing a continuous web through the machine and severing means having two cutting edges in spaced relation to simultaneously shear the web, one of the cutting edges having a projection adapted to notch the web.

2. In an envelope machine, the combination of means for advancing a continuous web through the machine, severing means having two cutting edges in spaced relation to simultaneously shear the web, one of the cutting edges having a projection adapted to notch the web, and means for adjusting the projection with reference to the web.

3. In an envelope machine, the combination of means for advancing a continuous web through the machine, a revolving knife having cutting edges in spaced relation and a cooperating die whereby the web is sheared simultaneously in two lines spaced from each other, the knife having a projection at one edge adapted to notch the web.

4. In an envelope machine, the combination of means for advancing a continuous web through the machine, a revolving knife having cutting edges in spaced relation, a cooperating die whereby the web is sheared simultaneously in two lines spaced from each other, the knife having a projection at one edge adapted to notch the web, and means for adjusting the knife and die with reference to the web.

In testimony whereof I affix my signature.

GEORGE FRANCIS HOGAN.
